United States Patent Office.

E. NICHOLSON, OF ROCKPORT, OHIO.

Letters Patent No. 66,515, dated July 9, 1867.

IMPROVEMENT IN GATE-LATCHES.

The Schedule referred to in these Letters Patent and making part of the same.

TO ALL WHOM IT MAY CONCERN:

Be it known that I, E. NICHOLSON, of Rockport, in the county of Cuyahoga, and State of Ohio, have invented certain new and useful improvements in Gate-Latches; and I do hereby declare that the following is a full and complete description of the construction and operation of the same, reference being had to the accompanying drawings making a part of this specification, in which—

Figure 1 is a view of the gate with the latch attached.

Figure 2 is an enlarged view of the latch.

Like letters of reference refer to like parts in the views.

The gate is of the ordinary construction, and can be of any desired size.

A is the pedestal, and A' the posts; the gate B being hinged in any desirable manner to the post. In fig. 2 C C' are plates which are secured to the post by means of the pins or bolts a, which pass through the post, the plates being placed, one on each side of said post, as shown in fig. 1. D represents the latch which extends through the post and through slots in the plates C C'. One end of this latch forms a handle, D', the other end resting in a slot or opening in the post A'. E is a spring which is secured to the inside of the plate C', and is allowed to move backward and forward by means of a slot or opening in the post. The end of this spring catches into a notch, e, in the latch. The upper edge of this latch forms shoulders b b', one on each side of the plate. When the handle D' is pressed down, the shoulder b pushes against the plate, which acts as a fulcrum, on which the latch moves. When the handle is pushed down in this way the spring will be moved out from the plate, the end catching in the notch e of the latch as stated, which raises the other end of the latch, as indicated by the dotted lines e', fig. 2, and the gate can then be easily opened. By removing the hand from the latch the spring will force it back in position, and also, with the aid of the shoulder b, prevent it from being pulled out. Thus when the gate swings to, the latch, by means of the spring, will catch into the slot above referred to.

It will be observed that as the handle of the latch is pressed down, the curved shoulder F, against which the spring acts, slides through the slot, and in so doing, describes the arc of a circle, as indicated by the dotted lines, and that the shoulder rests upon the lower end of the slot as it slides through; thus the latch is at all times held in its proper position while being operated, by the curvature of the shoulder, following the curve described, by the lifting of the latch, thus supporting the same through the whole distance it may move.

What I claim as my improvement, and desire to secure by Letters Patent, is—

The construction of a latch, D, provided with the shoulders b b', notch e, and curved shoulder F, as arranged in combination with the spring E, slotted plates C C', and gate for the purpose and in the manner as set forth.

E. NICHOLSON.
